APPARATUS FOR MINERAL SEPARATION

Maurice Constant, Scobey, Mont.

Application March 10, 1937, Serial No. 130,209

14 Claims. (Cl. 209—422)

My invention relates to improvements in machinery for separating gold or other metals from placer material, ground ore, pulp, slimes and other liquid mixtures.

5 The objects of my invention are to provide improved means to recover flour gold or the extremely fine metal particles, which by reason of their fineness or on account of being greasy, are difficult to recover by the ordinary sluices, tables, 10 jigs and other machines now in common use.

It is well known that in certain placer ground and in the pulp produced by grinding machines, ball mills, stamps, etc., there are often valuable quantities of flour gold or other metals which by 15 reason of fineness, or because of its chemical composition, or by reason of being coated with some oily substance, will remain in the liquid and be carried off in the tailings rather than precipitated upon the cloths, riffles, amalgam plates, 20 or other means provided to catch same.

20 It is one of the objects of my invention to provide means to capture such flour gold.

I accomplish these objects by the means illustrated in the accompanying drawings, in which—

25 Figure 1 is a sectional elevation of my apparatus on the line 1—1 of Figure 2, but for clearness omitting the sectioning of the baffle plates;

Figure 2 is a top or plan view with a portion of the upper part broken away to disclose the float discharge trough and pipe;

30 Figure 3 is a horizontal section on the line 3—3 of Figure 1, but with a portion of the screen over the riffle box broken away to disclose the construction of the riffles and with a part of the riffle grooves and the feed chutes omitted for simplicity;

Figure 4 is a cross section on the line 4—4 of Figure 1.

Similar numerals refer to similar parts throughout the several views.

40 My apparatus comprises a tank, with head-plate 2 and foot-plate 1 and side plates 3 and 4 preferably continuous with and forming a rounded bottom for the tank.

45 A feed hopper 6 is united to the head-plate of the tank and slopes downwardly into the tank and projects into the riffle box hereafter described.

An apron 6a is united to the head-plate 2 and 50 extends downwardly into the riffle box to form a part of the feed-chute and prevent splashing or surging of the pulp as it is fed into the tank from the hopper through the opening 6b.

A door-plate 83 is slidably mounted upon the 55 head-plate 2 and adapted when in its lowered position to close the opening 6b and prevent ingress of the pulp. It may be opened by raising it by the handle 84 and secured in its raised position by any suitable means.

60 Inside of the tank I mount a riffle box which

inclines downwardly from the feed end of the riffle box to and through the foot-plate 1 of the tank.

The riffle box includes a bottom board, or plate 50 with side boards 30 suitably united thereto. 5 The riffle box is supported upon rolls 48 and 57 carried by swinging arms 42 and 54 which are pivoted upon shafts 44 and 55 the ends of which are secured in suitable bearing plates 45 and 58 united to the sides of the tank so as to permit a 10 free swinging movement of the riffle box lengthwise when vibrated by the eccentric 72 which is driven by a shaft 73. An eccentric strap 71 is mounted upon the eccentric 72 and to an arm 70 pivotally connected to the link 68 by a pivot 15 69. The opposite end of the link 68 is pivotally united to a bracket 84 riveted to one end of the riffle box by rivets 63. A spring 61 has one end united to the riffle box and its opposite end united to the tank in order to smooth the vibrative 20 action of the riffle box to some extent.

The tank is preferably constructed with a length and depth of about twelve feet which will allow the riffle box to be about twelve feet long. I prefer to make the riffle box about four feet wide 25 and mount it in a tank about six feet wide. This will afford a space of about one foot on each side of the riffle box. The riffle box is preferably mounted in the tank at a depth of from four to ten feet below the water level.

30 The lower end of the riffle box projects outwardly through the foot-plate of the tank and into a tailings chamber 10 which may be formed integral with or suitably united to the tank and in which an elevator is mounted which can carry 35 the tailings upwardly and discharge them into any desired bin or carrier.

The side boards 30 of the riffle box are preferably a foot or more in height and extend the full length of the riffle box. They act to guide the 40 incoming stream or current of pulp downwardly through the tank and to discharge the pulp through the discharge opening in the foot-plate.

About halfway up the sides of the riffle box I 45 mount a screen 31 preferably of about ten mesh, which will prevent any large pieces of rock from settling in the riffles, but will readily permit the fines to settle through it and be precipitated upon the riffles.

In order to capture the fines, I provide a longitudinal groove 81 extending lengthwise of the bottom board 50 in the middle thereof with oblique branches 82 extending outwardly and to the rear.

50 These grooves are preferably rectangular but 55 may be of any desired section.

To discharge the precipitates from the riffle box I provide an opening at the lower end of the groove 81 with a short pipe secured therein extending downwardly therefrom. An outlet pipe 60

39 is secured in the bottom of the tank and a rubber or flexible hose 40 is used to connect the pipe 41 in the bottom of the riffle to the outlet pipe 39. A manually operable valve 38 is mounted 5 in the pipe 39 by which the opening thereof may be regulated as desired.

Upon the bottom board of the riffle box, beyond the outlet 41 I mount a fine screen 32 even with the top of the board 50 with a settling chamber 33 below it which may be filled with buckshot 33 supported by a coarser screen 34 so that any fines which are precipitated but not carried off by the outlet 41 may be caught in this screen chamber and discharged through a cone 35 and pipe 36 15 with a manually operable valve 37 mounted therein.

The tailings elevator may be of any desired type in common use. I prefer an elevator having an endless belt 7 passing over upper and lower 20 pulleys or sprockets 16 and 17 carried by shafts 15 and 14. The belt 7 carries buckets 8 which may be of any desired size and shape.

In order to stabilize the body of water in the tank, I mount in the tank a plurality of transverse baffle-plates 29 which may be secured in place by angle irons, lugs, or other suitable means and which extend to the bottom of the tank at the sides of the riffle box, and also extend upwardly nearly to the water level.

30 Each baffle 29 extends clear across the tank above the riffle box, but has a portion cut away to permit free vibration of the riffle box.

If desired, the baffles may be so constructed as to have a portion extending into the upper part of 35 the riffle box between the side boards. I prefer to have the middle portion of the baffle-plates terminate slightly above the side boards.

In order to prevent deposition of fines upon the bottom of the tank, and to facilitate upward 40 movement of any floatable particles of metal, I provide pipes 76, 77, 77' and 77'' to introduce into the bottom of the tank a continuous stream of clear water which will move upwardly and laterally. This movement of the fresh water will 45 also aid in confining the current of pulp to the riffle box.

At the top of the baffles 29 I mount a screen 28 preferably from one-fourth to one-half an 50 inch below the water level and which extends the full width and nearly the full length of the tank. This screen will permit the upward passage of any floating particles of metal that by reason of chemical composition or being coated with any oily or greasy substance, are inclined to float.

55 This screen is preferably of rather fine mesh but may be of any desired fineness.

The sides of the screen 28 are preferably covered with plates or planks 28' so as to confine the upward movement of the fine particles and the 60 fluid to the middle portion of the tank.

Brackets 24 and 19 are united to the head and foot-plates of the tank and carry shafts 23 and 21 upon which wide belt pulleys 22 and 18 are mounted which carry a flat belt 26. The belt 26 65 is fitted with a plurality of transverse bars or rakes 27 of just sufficient length to rake the screen 28 and carry any metal particles which have come upwardly through the screen along to the foot of the screen where they are deposited 70 in a trough 90 and discharged from the tank through a pipe 86 into a strainer or dewaterer 87 which may be secured to the outside of the tank by a strap 88.

A large discharge pipe 10a is secured in the bottom of the tailings chamber 10 through which

the chamber 10 may be flushed out when necessary. An overflow outlet 10b is provided near the upper end of the chamber 10 to carry off any excess fluid in case of overcharge, and to maintain the water level in the tank at the 5 desired height.

Suitable means are provided to drive the screen rake, to vibrate the riffle box and to operate the elevator, but as such means form no part of my invention, I have omitted them for clearness. 10 Any or all of these pieces of apparatus may be driven by electric motor or other prime mover as desired, or by belting.

In the operation of my apparatus, the tank is first filled with clear water to the desired water 15 level. The door 83 is then opened and the pulp fed into the tank from the feed hopper and into the riffle box. At the same time, the driving means are set in operation to actuate the vibrator, elevator and screen rake.

As the elevator operates, its buckets carry out a certain amount of water, thus allowing liquid from the riffle box to pass into the tailings chamber. This, in connection with the feeding action of the pulp into the riffle box, will cause a stream 25 or current of pulp to pass along through the riffle box and the baffles in the tank will act to prevent a spreading out or diversion of this stream.

At the same time, any floatable particles will be free to rise in the water of the tank between the 30 baffles and to and through the upper screen where they will be acted upon by the rake and carried to the trough 90 and thence to the strainer 87.

The heavier particles of metal will settle through the screen 31 and down into the grooves 35 31 and 32 where they will travel gradually downwardly to the discharge pipe 41.

The waste will be carried out of the lower end of the riffle box into the tailings chamber and disposed of by the elevator.

In practice, it will be necessary to vary the timing of the current, the proportion of feed and of clear water introduced into the tank, the speed of the rake and the elevator and the speed of the vibration of the riffle box to meet the requirements of each particular case, it being well known to those skilled in the art that there is a great diversity in the size and character of the metal particles in different placer districts and in the pulps or ground ores coming from different districts and different grinding processes.

One of the great advantages of my apparatus is the ease with which all the varying elements may be controlled and regulated so as to properly proportion the depth of water, the time allowed 55 for precipitation, the proportion of clear water to pulp, etc.

While the reason for it is perhaps not entirely clear, I have found in practice that a good precipitation of flour gold can be obtained under a 60 head or pressure of from four to ten feet of water which could only be partially precipitated or not precipitated at all at or near the surface of the water.

It is likewise obvious that my provisions for 65 an upwardly moving body of clear water at the sides of the riffle box, will tend to prevent lateral spreading of the current therein, and that the lateral closures at the top of the tank will tend to cause upwardly moving particles to be carried 70 to the middle of and through the upper screen. As a small amount of water will be carried out of the tank by the action of the rake, there will be a constant slowly rising current of clear water 75 at the sides of the riffle box which will facilitate

the upward movement of the fine particles without interfering with the precipitation of the heavier matter in the riffle box.

I use the term "submerged" in the claims, to indicate any substantial submergence of the riffle box, and "deeply submerged" to indicate any depth in excess of four feet.

It is obvious that many modifications may be made of my apparatus without departing from the spirit of my invention, and I do not limit my claims to the precise forms or proportions shown or described herein.

Neither do I limit my process to the recovery of particles of virgin metal, because it is obvious that both the flotation and the precipitation may be applicable to various chemical combinations of precious metals and minerals.

I claim:

1. In a machine for recovering fine particles of metal from an aqueous mechanical solution thereof, the combination with a tank containing a body of aqueous liquid and having an inclined submerged riffle box mounted therein, of means for slowly passing a stream or current of such solution along and through the riffle box under a substantial head of water, and for drawing off the precipitant at the lower end of the riffles, a series of transverse baffles secured in the tank adapted to restrict longitudinal movement of fluid therein, above and at both sides of the said current, and means for vibrating the riffle box.

2. A machine for the recovery of flour gold or the like, comprising a tank containing a large body of water with outlet means adapted to maintain a constant level of the liquid therein, an inclined submerged vibratory riffle box mounted in the tank, an intake united to the tank adapted to conduct a stream of pregnant solution into the upper end of the riffle box, a tailings chamber with elevator therein adapted to receive and carry off the barren solution from the lower end of the riffle box, discharge means at the lower end of the riffle box adapted to carry the precipitates from the tank, a horizontal screen secured in the tank slightly below the water level adapted to permit passage of lighter particles of mineral ascending in the solution, and a rake adapted to carry the float from the screen.

3. A machine for the recovery of flour gold or the like, comprising a tank containing a large body of water with outlet means adapted to maintain a constant level of the liquid therein, an inclined submerged vibratory riffle box mounted in the tank, an intake united to the tank adapted to conduct a stream of pregnant solution into the upper end of the riffle box, a tailings chamber with elevator therein adapted to receive and carry off the barren solution from the lower end of the riffle box, discharge means at the lower end of the riffle box adapted to carry the precipitates from the tank, a horizontal screen secured in the tank slightly below the water level adapted to permit passage of lighter particles of mineral ascending in the solution, means to discharge the float into a strainer, and intake pipes leading into the bottom of the tank to supply fresh water thereto below the riffle box.

4. A machine for the recovery of flour gold or the like, comprising a tank containing a large body of water with outlet means adapted to maintain a constant level of the liquid therein, an inclined submerged trough mounted in the tank, intake means united to the tank adapted to conduct a stream of pregnant solution to the upper end of the trough, discharge means adapted to

carry off separately from the lower end of the trough the barren solution, a horizontal screen secured in the tank slightly below the water level adapted to permit passage of lighter particles of mineral ascending in the solution, and a rake adapted to carry the float from the screen.

5. A machine for the recovery of flour gold or the like, comprising a tank containing a large body of water with outlet means adapted to maintain a constant level of the liquid therein, an inclined submerged vibratory riffle box mounted in the tank, an intake to the tank adapted to conduct a stream of pregnant solution into the upper end of the riffle box, a tailings chamber with elevator therein adapted to carry off from the lower end of the riffle box the barren solution, discharge means at the lower end of the riffle box adapted to carry the precipitates from the tank, a horizontal screen secured in the tank slightly below the water level adapted to permit passage of lighter particles of mineral ascending in the solution, a rake adapted to carry the float from the screen, intake pipes leading into the bottom of the tank to supply fresh water thereto below the riffle box, and a plurality of transverse baffle plates extending across the tank above the riffle box, and downwardly at each side of the riffle box, adapted to restrict longitudinal movement of the liquid outside of the riffle box.

6. A machine for the recovery of fine particles of metal such as flour gold or the like from an aqueous mixture containing same, comprising a tank containing a relatively large body of water with an outlet at the desired water level therein, a submerged riffle box mounted in the tank sloping downwardly from the intake, an intake to lead the pregnant mixture into the riffle box having a gate to regulate the quantity and rate of flow so as to permit subsidence and deposit of metal in the riffle box by gravity, baffles mounted in the tank extending above and at the sides of the riffle box at right angles thereto to confine the flowing mixture substantially to the riffle box, an outlet in the floor of the lower end of the riffle box to carry off the precipitate, and an outlet in the tank near the foot of the riffle box to carry off the tailings.

7. A machine for the recovery of fine particles of metal such as flour gold or the like from an aqueous mixture containing same, comprising a tank containing a relatively large body of water with an outlet at the desired water level therein, a submerged riffle box mounted in the tank sloping downwardly from the intake, an intake to lead the pregnant mixture into the riffle box having a gate to regulate the quantity and rate of flow so as to permit subsidence and deposit of metal in the riffle box by gravity, baffles mounted in the tank extending above and at the sides of the riffle box at right angles thereto to confine the flowing mixture substantially to the riffle box, a primary outlet in the floor of the lower end of the riffle box to carry off the precipitate, a secondary outlet in the floor of the riffle box comprising a fine screen united to and even with the upper face of such floor, a coarser screen secured to such floor and spaced from the first screen with buckshot or its equivalent interposed between the two screens to catch and detain the metal particles, an outlet in the tank near the foot of the riffle box to carry off the tailings.

8. A machine for the recovery of fine particles of metal such as flour gold or the like from an aqueous mixture containing same, comprising a tank containing a relatively large body of water

with an outlet at the desired water level therein, a submerged rifle box mounted in the tank sloping downwardly from the intake, an intake to lead the pregnant mixture into the rifle box having a gate to regulate the quantity and rate of flow so as to permit subsidence and deposit of metal in the rifle box by gravity, baffles mounted in the tank extending above and at the sides of the rifle box at right angles thereto to confine the flowing mixture substantially to the rifle box, an outlet in the floor of the lower end of the rifle box to carry off the precipitate, a tailings chamber at the rear of the tank, an outlet in the tank near the foot of the rifle box to carry the tailings into such chamber and means to discharge the tailings therefrom.

9. In a machine of the class described, the combination with a stationary tank having a fluid inlet and outlet and containing a body of aqueous liquid, of an inclined riflebox comprising a tight bottom with riffles formed therein, and with sides extending upwardly therefrom, a screen mounted in the riflebox spaced above the bottom and extending from side to side, a feed chute to deliver pulp to the upper end of the screen, means comprising stationary transverse baffle plates for guiding a stream of liquid downwardly along the screen, an outlet for separately drawing off the precipitant from the bottom of the riflebox and an elevator to continuously remove the coarser material mingled with fluid from the lower end of the screen, said riflebox being submerged in liquid to a depth sufficient to cause deposition of the flour gold, and means for vibrating the riflebox longitudinally without moving the tank.

10. In a machine of the class described, the combination with a stationary tank having fluid inlets at the bottom of the tank and outlets near the top thereof, and containing a body of aqueous liquid, of an inclined riflebox comprising a tight bottom with riffles formed therein, with sides extending upwardly therefrom, a screen mounted in the riflebox spaced above the bottom and extending from side to side, a feed chute to deliver pulp to the upper end of the screen, means comprising stationary transverse baffle plates for guiding a stream of liquid pulp downwardly along the screen, means for separately drawing off the precipitant from the bottom of the riflebox and the coarser material from the lower end of the screen, said riflebox being submerged in liquid to a depth sufficient to cause deposition of the flour gold, and means for vibrating the riflebox longitudinally without moving the tank.

11. In a machine of the class described, a stationary tank having fluid inlets at the bottom of the tank and outlets near the top thereof, and containing a body of aqueous liquid, an inclined riflebox comprising a tight bottom with riffles formed therein, with sides extending upwardly therefrom, a screen mounted in the riflebox spaced above the bottom and extending from side to side, a feed chute to deliver pulp to the upper end of the screen, a series of transverse baffles mounted in the tank spaced above the riflebox but with sides extending downwardly at both sides of said riflebox to confine and guide the stream of pulp downwardly along the screen, means for separately drawing off the precipitant from the bottom of the riflebox and the coarser material from the lower end of the screen, said riflebox being submerged in the solution to a

depth sufficient to cause deposition of the flour gold, and means for vibrating the riflebox longitudinally without moving the tank.

12. In a machine of the class described, a stationary tank having a fluid inlet at the bottom thereof and outlet near the top thereof and above the baffles hereinafter mentioned and containing a body of aqueous liquid, an inclined submerged riflebox comprising a tight bottom with riffles formed therein, with sides extending upwardly therefrom, a screen mounted in the riflebox spaced above the bottom and extending from side to side, a feed chute to deliver pulp to the upper end of the screen, a series of transverse baffles mounted in the tank spaced above the riflebox but with sides extending downwardly at both sides of said riflebox to confine and guide the stream of pulp downwardly along the screen, outlets for separately drawing off the precipitant from the bottom of the riflebox and the coarser material from the lower end of the screen, said riflebox being submerged in the solution to a depth sufficient to cause deposition of the flour gold, and means for vibrating the riflebox longitudinally without moving the tank.

13. In a machine of the class described, a stationary tank having a lower fluid inlet and an upper outlet near the top thereof and above the baffles and containing a body of aqueous liquid, an inclined vibratory riflebox comprising a tight bottom having riffles formed therein and with sides extending upwardly therefrom, a screen mounted in the riflebox spaced above the bottom and extending from side to side, a feed chute to deliver pulp to the upper end of the screen, a series of stationary transverse baffles mounted in the tank spaced above the riflebox but with sides extending downwardly at both sides of said riflebox to confine and guide the stream of pulp downwardly along the screen and to confine the upward movement of the fluid from the lower inlet on its way to the upper outlet, and outlets for separately drawing off the precipitant from the bottom of the riflebox and the coarser material from the lower end of the screen, said riflebox being submerged in the solution to a depth sufficient to cause deposition of the flour gold.

14. A machine for the recovery of flour gold or the like, comprising a stationary tank containing a large body of water having an outlet near the top to maintain a constant level of the liquid therein, an inclined, submerged vibratory riflebox substantially narrower than the tank mounted in the tank, an intake secured to the tank at the upper end of the riflebox to conduct a stream of pregnant solution into that end of the riflebox under a substantial head and having a manually operable gate to regulate the flow of pregnant solution into the tank, a tailings chamber with elevator therein adapted to carry off from the lower end of the riflebox the barren solution, a plurality of transverse baffle plates extending across the tank above the riflebox and downwardly at each side of the riflebox to restrict longitudinal movement of the liquid in the tank outside of the riflebox without obstructing the vertical movement of the liquid in the tank, the tops of said baffles having a uniform height and being located slightly below the first mentioned outlet.
